UNITED STATES PATENT OFFICE.

FREDERICK E. STANLEY, OF WATERBURY, CONNECTICUT, ASSIGNOR TO SCOVILL MANUFACTURING COMPANY, OF WATERBURY, CONNECTICUT, A CORPORATION OF CONNECTICUT.

FLEXIBLE-SHANK TACK-BUTTON.

1,292,913.

Specification of Letters Patent. Patented Jan. 28, 1919.

Application filed July 26, 1917. Serial No. 182,971.

To all whom it may concern:

Be it known that I, FREDERICK E. STANLEY, a citizen of the United States, residing at Waterbury, in the county of New Haven and State of Connecticut, have invented a certain new and useful Improvement in Flexible-Shank Tack-Buttons, of which the following is a full, clear, and exact description.

10 This invention relates to that class of buttons which are fastened to or set on goods by means of tacks, and commonly known as tack fastened buttons.

15 The object of the invention is to provide a flexible button of this class; that is to say, one in which the button head is movable longitudinally and laterally with relation to its shank and capable of rotation thereon.

20 The invention consists of a tack fastened button in which the connection between the head and shank is flexible, the shank of which comprises a hollow anvil and an eyelet-like spacer or foot which are rigidly united and adapted to receive and clench the 25 fastening tack so as to set the button, the button head being applied to the shank before the anvil is clenched in the spacer or foot and in such manner that the button head may have longitudinal movement on the shank and also a lateral or tilting movement thereon and be capable of rotating about it as an axis, as I will proceed now to explain and finally claim.

25 In the accompanying drawings illustrating the invention, in the several figures of which like parts are similarly designated, Figure 1 shows in plan view and side elevation the spacer or foot, and Fig. 2 shows in top plan view, side elevation and bottom 40 plan view the anvil which when united with the spacer or foot forms the shank of the button. Fig. 3 shows in plan view and side elevation the back or collet of the button. Fig. 4 shows in plan view and side elevation 45 the cap. Fig. 5 shows in transverse section and bottom plan view the assembled button. Fig. 6 shows on a larger scale the assembled button set on pieces of fabric and with the button head drawn up to the farthest extent of its upward movement, the dotted lines illustrating one way in which the button head is capable of being tilted on its shank.

50 In the preferred construction and the one here selected for illustrating the invention,

the back or collet 1 of the button may be of any approved shape and material, usually of metal, and provided with a central opening 2. The cap 3 likewise may be of any usual or approved construction and adapted to be closed down over the edge of the back as shown in Figs. 5 and 6. The hole 2 in the back is to receive the shank of the button, by means of which the button is capable of being attached to a garment or other object. The shank in the present invention comprises a steel or other relatively hard metal hollow device 4, comprising a closed flat top portion 5, and the tubular portion 6 of such construction as to permit it to be expanded within an eyelet-like spacer or foot 7 having the tubular portion or barrel 8 and the outwardly flared or concave base 9. The top portion 5 receives the point of the tack 10 in the setting operation and upsets it, as indicated in Fig. 6, and for this reason this portion 5 is herein referred to as an anvil. The top portion 5 of the anvil flares out from the tubular portion 6, and the tubular portion or barrel of the spacer or foot 7 preferably is reduced in thickness to a minimum consistent with strength and is forced up against the base of the flaring top so as to be substantially flush therewith and to avoid the presentation of any appreciable shoulder 85 or obstacle to the free movement of the button head on its shank.

55 In assembling the parts, the back or collet 1 and the anvil 4 are engaged by passing the tubular portion of the anvil through the hole 2 so as to project beyond the same and while the flared portion or top is within the back. Then the tubular portion of the anvil is inserted in the spacer or foot 7 and the two drawn together so that there can be no possible relative movement, and then the tubular portion of the anvil is spread or expanded, as indicated in Figs. 5 and 6, so as to render the union of the two permanent and immovable, and then the cap 3 is applied to the back, and the button is then ready to receive any desired finish and to be applied to a garment or other goods.

60 As shown in the sectional view, Fig. 5, the button head gravitates upon its shank, but when strain is placed upon the button head it may move outwardly to the limit of its shank, as indicated in Fig. 6, and not only so, but in either position the button head is capable of lateral movement on the

shank, for example, as indicated by dotted lines in Fig. 6, and moreover it may always be turned around the shank as upon an axis.

It will be observed that in my invention 5 the two-part shank composed of the hollow anvil having the flaring top and the spacer or foot having the flared base, provide by means of the top and base the only limitations of movement of the button head thereon, and thus a relatively wide range of longitudinal movement as well as of lateral movement of the button on its shank is secured, and by means of a very simple construction.

10 15 The invention is susceptible of variations in structural details, so long as the intimate union and substantially unbroken profile of the shank are preserved.

What I claim is:—

20 1. A flexible shank tack fastened button, having a button provided with a back or collet having a central opening, and a shank composed of an anvil having a flared top portion located within the button head and a tubular portion extending outside the same through the central opening in the back or collet, and a spacer or foot applied externally to the anvil and having a flared 25 base, the anvil and spacer or foot being rigidly connected, the external profile of the thus completed shank being substantially uniform and unbroken between the flared top of the anvil and the flared base of the spacer or foot, whereby the button head is

30 35 movable longitudinally, laterally and rotatably with relation to the shank, said longitudinal motion being limited in opposite directions by contact of the button head with the flared top portion of the shank and the base of said shank respectively.

40 45 2. A flexible shank tack fastened button, having a button head, the back or collet of which is perforated, and a shank composed of an anvil having a flared top portion located within the button head and limiting the outward movement of the head toward such top and a tubular expansible portion extending outside the same, and a spacer or foot having a tubular portion and a flared base and applied externally to the anvil, the tubular portion of the anvil being expanded 50 within the spacer or foot to rigidly connect the two, the tubular portion of the spacer or foot extending up to the flared portion of the anvil and affording substantially an 55 unbroken and uniform external surface on which the button head may move longitudinally and laterally between the said flared portion of the anvil and the flared base of the spacer or foot and rotatively upon said shank as an axis.

In testimony whereof I have hereunto set my hand this 24th day of July, A. D. 1917.

FREDERICK E. STANLEY.

Witnesses:

PERCY WARNER,
E. A. HYDE.

It is hereby certified that in Letters Patent No. 1,292,913, granted January 28, 1919, upon the application of Frederick E. Stanley, of Waterbury, Connecticut, for an improvement in "Flexible-Shank Tack-Buttons," an error appears in the printed specification requiring correction as follows: Page 2, line 21, claim 1, after the word "button" insert the word *head*; and that the said Letters Patent should be read with this correction therein that the same may conform to the record of the case in the Patent Office.

Signed and sealed this 25th day of February, A. D., 1919.

[SEAL.]

F. W. H. CLAY,

Acting Commissioner of Patents.
